Patented Apr. 16, 1974

231,352

COMBINED RECEPTACLE AND COVER FOR PORTABLE TOILET

Bernard C. Sharp, White Plains, N.Y., assignor to
Sears, Roebuck and Co., Chicago, Ill.

Filed Sept. 26, 1972, Ser. No. 293,660

Term of patent 14 years

Int. Cl. D23—02

U.S. Cl. D23—48

Fig. 1

Fig. 5.

Fig. 4.

Fig. 3.

Fig. 2.

FIG. 1 is a perspective view of a combined receptacle and cover for portable toilet showing my new design;

FIG. 2 is a side elevational view thereof, partly in cross section;

FIG. 3 is a fragmentary cross-sectional view thereof, taken on line 3—3 of FIG. 2;

FIG. 4 is a cross-sectional view taken on line 4—4 of FIG. 2; and

FIG. 5 is a top perspective view of the cover.

The broken line representation of a bail in FIGS. 1 and 2 is for purposes of illustration only.

I claim:

The ornamental design for a combined receptacle and cover for portable toilet, as shown and described.
